US0D1113555S

(12) **United States Design Patent** (10) **Patent No.:** **US D1,113,555 S**
(45) **Date of Patent:** **** Feb. 17, 2026**

(54) **GEMSTONE**

(71) Applicant: **Walking Tree Design Studio USA Inc.**,
Dover, DE (US)

(72) Inventor: **Ankit Hitesh Mehta**, Mumbai (IN)

(73) Assignee: **Walking Tree Design Studio USA Inc.**,
Dover, DE (US)

(**) Term: **15 Years**

(21) Appl. No.: **29/959,298**

(22) Filed: **Aug. 23, 2024**

(51) LOC (15) Cl. **11-01**

(52) U.S. Cl.

USPC **D11/90**
